REFRIGERANT CONTAINER CONSTRUCTION
FOR RAILWAY REFRIGERATOR CARSAlfred L. Thompson, Munster, Ind., assignor to
Standard Railway Equipment Manufacturing
Company, Chicago, Ill., a corporation of Dela-
ware

Application November 13, 1946, Serial No. 709,619

13 Claims. (Cl. 62—17)

1
The invention relates to railway refrigerator cars and more particularly to the so-called top bunker refrigerator car, as illustrated in Bonsall Patent No. 2,136,999 of November 15, 1936, upon which my invention is an improvement.

In the Bonsall type of refrigerator car the refrigerant container is positioned adjacent the roof and one side wall of the car and a horizontal partition is spaced below the refrigerant container and another vertical partition is positioned adjacent the side wall to form a continuous flue from below the container to the space below the floor rack of the car so that air cooled by the refrigerant in the container descends through the side wall flue to below the floor rack, and being warmed by the lading, rises through the lading and lading compartment of the car and returns to the space below the refrigerant container, where it is cooled again and repeats the cycle.

Wet ice is frequently used as a refrigerant in such top bunker refrigerator cars and salt is used with the wet ice to accelerate melting and thereby increasing refrigeration, which salt corrodes the metallic refrigerant containers necessitating their removal and replacement every few years.

Refrigerator cars are frequently iced while in transit, therefore, it is imperative that they be iced or reiced quickly so as not to delay the train.

One object of my invention is to provide a hatch in the roof of the car communicating with the interior of the refrigerant container wherein the hatch opening is as large as the container which accomplishes two objects: first: it expedites loading of the refrigerant in the container, thereby reducing the time and expense necessary to load the refrigerant container, and secondly, it makes it possible to remove and replace the refrigerant container through the roof of the car instead of into the interior of the car as is now customary, thus reducing the time and expense of such removal and replacement.

A further object of the invention is to attach the refrigerant container to a fixed part of the car in such a way that the refrigerant container can be detached from such fixed part of the car from the exterior of the car, thus simplifying removal and replacement of the container. A further object is to provide attaching means, such as rivets, which can be applied or removed from the exterior of the car, but which are positioned so that a loose rivet will not allow water to wet the insulation of the car, but instead enters the refrigerant container. Insulation, when wet, loses part of its insulating value.

2
Another object of the invention is to provide such attaching means without the use of welding, as welding is liable to ignite the insulation and is, therefore, dangerous.

- 5 My invention applies to a refrigerant container whether wet ice, dry ice, eutectic ice or mechanical refrigeration is used in the container. Sometimes a lining is used as an insulation between dry ice and the bottom of the container so as to retard the sublimation of the dry ice. Another object of the invention is to provide a container wherein the lining, if used, can be installed or removed from the exterior of the car through the hatch opening.
- 10 Another object of the invention is to provide a refrigerant container which can be assembled as a unit and applied to the car from the exterior thereof as a unit and wherein such unit can be attached to the car from the exterior thereof.
- 15 Another object of the invention is to provide a refrigerant container which extends above the general plane of the roof so as to provide a baffle to prevent water, cinders or other foreign matter from entering the refrigerant container, and furthermore to form such baffle as to provide a reinforcement around the periphery of the hatch opening and to attach the refrigerant container to the part of the baffle reinforcement above the general plane of the roof so that said attachment can be removed from the exterior of the car, and furthermore to so form the container that after said attachment is removed the container can be removed from the exterior of the car.
- 20 Any desirable lid or gasket arrangement between the lid and the hatch frame or any desirable locking or ventilating means may be used with my improved refrigerant container.

In the drawings:

40 Figure 1 is a perspective view of my improved refrigerant container applied to a railway refrigerator car with parts broken away to illustrate the construction thereof.

45 Figure 2 is a lateral section of a railway refrigerator car incorporating my improved refrigerant container.

Figure 3 is a longitudinal section of a refrigerator car showing the adjacent ends of two of my improved refrigerant containers, which figure also shows the construction of the roof of the car between the containers.

50 Figure 4 is a longitudinal cross section of a car showing a plurality of my improved containers.

Figure 5 is a plan view of Figure 1.

55 Figures 6, 7, 8 and 9 show modified structures

including insulation hereinafter specifically described.

In the drawings the side wall 2 and roof 3 of the car are connected by the side plate 4. The refrigerant container 5 is positioned adjacent the side wall 2 and roof 3 of the car and a horizontal partition 8 is spaced below the refrigerant container 5 so as to provide the flue 9 which communicates with the flue 10 between the vertical partition 11 and the side wall 12 proper of the car. The air in the flue 9, being cooled by the refrigerant in the container 5, descends through the flue 10 underneath the floor racks (not shown) from whence, being warmed by the lighting, rises and enters the flue 13 through the opening 14.

The carlines 18 extend between and are supported by the side plates 4 of the car, such as by the connecting member 19 and rivets 20. The purlins 21-22 extend between the carlines 18 and are secured thereto, preferably by welding (before the insulation is installed), so that the spaced carlines 18 and spaced purlins 21-22 form a rigid frame 23. The refrigerant container 5 (whether foraminous or solid) has the major portion thereof below the roof sheets 24 so as to obtain the necessary cubical capacity thereof and so that the walls of the container 5 will be in heat transfer relation between the refrigerant in the container 5 and the flues 9 and 13. The side (27) and end (28) vertical walls of the refrigerant container 5 extend through and above the frame 23 formed by the carlines 18 and purlins 21-22 and the overall width and length of the container are no greater at any place than the overall width and length of the opening in the frame 23 so that the refrigerant container 5 can be lowered vertically into position through the frame 23 from the outside of the car, and likewise, can be removed vertically from the car through the hatch opening 23. In other words, all horizontal dimensions of the container are such that the container may be moved vertically through the hatch opening 23 into or out of service position in the car without disturbing the roof sheets nor the reinforcing member. This is a material advantage in maintaining railway refrigerator cars.

The side walls 27 of the container 5 are adjacent the purlins 21-22, respectively, so as to be braced thereby but are not secured to the purlins. Likewise the end walls 28 of the container 5 are positioned adjacent the carlines 18 so as to brace the container but are not secured to the carlines 18. The roof sheets 24 are provided with marginal upstanding flanges 30 which are adjacent to and preferably in contact with the portion 29 of the refrigerant container 5 above the roof sheets 24.

The reinforcing member 31 extends around the periphery of the upper part of the refrigerant container 5, which reinforcing member has spaced apart parts 32 and 33 straddling the upstanding flange 30 of the roof sheet 24 and the portion 29 of the container above the roof sheet 24, all of which are secured together by the horizontally disposed rivets 34. These rivets 34 may be countersunk on the inside of the container if desired. The reinforcing member 31 is provided with a horizontal flange 36 which overlaps the roof sheet 24 and this flange 36 is positioned directly above the carlines 18 and purlins 21-22, respectively, so that the weight of the container 5 and the refrigerant therein is suspended from the reinforcing member 31 by the rivets 34, which

weight is transferred to the horizontal flange 36 and thence directly to the purlins 21-22 and the carlines 18, respectively, so that in the final analysis the carlines 18 and purlins 21-22 directly support the refrigerant container 5 and the refrigerant therein.

The rivets 34 are horizontally disposed so that they may be easily driven by hand or a squeezer, but in case of a loose rivet any water passing around such loose rivet will drain into the container 5 and thence through the flues 9 and 10 to the lower part of the car, but my construction is such that this water cannot contact the insulation of the car.

The container 5 is supported and reinforced by a cradle arrangement which comprises a plurality of reinforcing U-shaped members 40, the bottom portions 41 of which support the refrigerant container 5 but is not secured thereto, and the arms 42-43 of which prevent outwardly bulging of the side walls 27 of the container 5. These arms 42-43 are not secured to the side walls 27 of the container 5. The upper portions of the arms 42-43 are welded to and supported by the purlins 21-22, respectively. It may be desirable to slightly taper the walls of the container and the associated parts so that the lower portion of the container will be smaller than the upper part thereof to expedite installation and removal of the container from the car.

The hatch plug 46 preferably fits between the several portions of the reinforcing member 31 and is supported by a lid 47 which rests on top of the reinforcing member 31. A gasket 48 may be provided between the lid and reinforcing member if desired. The metallic lid 47 can be hinged to the car in any desirable manner but must be constructed and arranged so that when the lid is in open position neither the lid nor the plug will interfere with the installation of the container or the removal thereof from the car.

The roof sheets 24 on either side of the carline 18 abut over the carline and are preferably secured to each other and the carline by a single row of welding 49.

Each carline 18, as shown, comprises a metallic bar of rolled channel section and positioned so that the web 50 thereof braces the vertical wall 25 of the container 5 and holds it in place, while the upper flange 51 thereof supports the flange 36 of the reinforcing member 31 and the lower flange 52 thereof supports the insulation 53 through the medium of the ceiling 54.

The purlin 21 illustrated in Figure 2 comprises an upper horizontal portion 60 upon which the roof sheets 24 rest, a vertical portion 61 which braces the wall 27 of the container 5, a lower horizontal portion 62 extending outwardly from the container to provide stiffening means and a portion 63 depending from the outer margin of the portion 62. The cradle members 40 are attached to either or both of the arms 62-63 and are supported and braced thereby. In this construction the container 5 may be moved vertically in or out of the cradle without disturbing the cradle and furthermore the wall 27 of the container 5 is flat without any projections which would interfere with the loading of the refrigerator into the container 5. The nailing strip 64 which supports the ceiling 54 is attached to the purlin 21.

Figure 6 shows a modified structure wherein insulation 68 has been inserted between the roof sheet 69 and purlin 10; and between the roof sheet 69 and the reinforcing member 11; and

wherein other insulation 72 has been inserted between the roof sheet flange 73 and reinforcing member 71, which insulation also preferably extends between the upper part of the container wall 76 and reinforcing member 71. The object of the insulations just described is to retard heat transfer from outside the car through the roof sheet 69 and container wall 76 to the interior of the car or into the refrigerant in the container. Wood, fibre board, Masonite, asbestos, plastic material, or any insulating material may be used as far as the invention is concerned.

Figure 7 is a modification of Fig. 6 wherein the reinforcing member 80 is made of plastic material which has insulating value thus only requiring insulation 81 between the roof sheet 82 and purlin 83 and insulation 84 between the roof sheet flange 85 and upper part of the container wall 86.

Figure 8 shows a modified structure wherein the reinforcing member is omitted and heat transfer between the roof sheet flange 91 and the upper part of the container wall 92 is prevented by the insulation 93 and the gasket 94, which is secured to the lid or opening cover 95. Insulation 96 is positioned between the roof sheet 97 and purlin 98.

Figure 9 is a modification of Fig. 8 wherein the wall sheet 100 of the container is formed with a marginal stiffening flange 101, and an insulating block 102 is provided which is recessed for the flange 101 and also for the flange 103 of the roof sheet 104. The gasket 105, which is secured to the lid 106, preferably engages the block 102 and the flange 101. In this modification the wall 100 of the container is bolted as at 107 to the flange 103 of the roof sheet. As plastic is a poor conductor of heat, the reinforcing member may be made of plastic instead of steel if desired.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A refrigerant container for use in a railway car having spaced carlines and spaced purlins secured together to form a frame and roof sheets supported by said frame; said container comprising vertical side walls and vertical end walls and a bottom, the distances over the side walls and end walls, respectively, of the container being substantially the same as the distances between the purlins and carlines, respectively, of the frame, and a reinforcing member straddling and secured to the upper margin of said walls and having a lateral flange overlapping the margin of said roof sheets supported by said frame, whereby the container may be installed in or removed from the car through the frame from the exterior of the car without disturbing the frame or roof sheets.

2. A refrigerant container for use in a railway car having spaced carlines and spaced purlins secured together to form a frame and roof sheets supported by said frame and formed with upstanding marginal flanges, said container comprising vertical side walls and vertical end walls extending above said frame, the distances over the side walls and end walls, respectively, of the container being substantially the same as the distances between the purlins and carlines, respectively, of the frame, whereby the container may be installed in or removed from the car through 75

the frame from the exterior of the car without disturbing the frame or roof sheets, a reinforcing member supported by said frame and provided with a part straddling the portions of said walls extending above said frame and the roof sheet flanges, and securing means passing through the straddling portion of the reinforcing member, the roof sheet flange and the portions of said walls extending above the roof sheets, whereby the container is suspended from the reinforcing member by said means.

3. A structure as defined in claim 2 wherein the reinforcing member is provided with a lateral part adapted to be positioned directly above said frame when applied to a car.

4. A structure as defined in claim 2 including a cradle suspended from said purlins and positioned so as to support said container without being secured thereto.

5. A structure as defined in claim 2 including a cradle suspended from said purlins and positioned so as to support said container and brace vertical walls thereof without being secured thereto.

6. In a railway car roof having a hatch opening therein formed by spaced frame members, metallic roof sheets resting upon and supported by said frame members and formed with upstanding flanges in the planes of the periphery of said opening, a refrigerant container comprising vertical walls, each having a portion thereof below the roof sheets substantially in contact with said frame members but not secured thereto and a portion thereof above said roof sheets substantially in contact with the flanges of the roof sheets, and securing means passing through the upstanding flanges of the roof sheets and the portions of the container walls above the roof sheets.

7. In a railway car roof having a hatch opening therein formed by spaced frame members, metallic roof sheets resting upon and supported by said frame members and formed with upstanding flanges in the plane of the periphery of said opening, a refrigerant container comprising vertical walls, each having a portion thereof below the roof sheets substantially in contact with said frame members but not secured thereto and a portion thereof above said roof sheets substantially in contact with the flanges of the roof sheets, 50 a reinforcing member straddling the portions of the container walls above the roof sheets and the upstanding flanges of the roof sheets, and securing means passing through the upstanding flanges of the roof sheets and the portions of the container walls above the roof sheets and the reinforcing member.

8. A structure as defined in claim 6 wherein all horizontal dimensions of the container are such that the container may be moved vertically through the hatch opening into or out of service position without disturbing the roof sheets.

9. A structure as defined in claim 7 wherein said reinforcing member is provided with a flange resting upon the portions of the roof sheets above the frame members.

10. A structure as defined in claim 7 wherein all horizontal dimensions of the container are such that the container may be moved vertically through the hatch opening into or out of service position without disturbing the roof sheets or reinforcing member.

11. In a railway car, the combination of a frame member having a horizontal arm and a vertical arm, a roof sheet resting upon said horizontal arm and formed with an upstanding flange in the

7
plane of the vertical arm, a refrigerant container having a vertical wall extending above the plane of the roof sheet, and horizontal securing means extending through said upstanding flange and the portion of the container above the plane of the roof sheet.

12. In a railway car, the combination of a frame member having a horizontal arm and a vertical arm, a roof sheet resting upon said horizontal arm and formed with an upstanding flange in the plane of the vertical arm, a refrigerant container having a vertical wall extending above the plane of the roof sheet, a reinforcing member straddling said upstanding flange and the portion of the container above the plane of the roof sheet, and horizontal securing means extending through said upstanding flange and the portion of the container above the plane of the roof sheet and the reinforcing member.

13. In a railway car, the combination of a frame member comprising an upper horizontal portion, an upper vertical portion depending from one margin thereof, a lower horizontal portion spaced

5

10

15

from the upper horizontal portion and a lower vertical portion depending from the last mentioned portion, a roof sheet resting upon said upper portion and formed with an upstanding flange in the plane of the upper vertical portion; a refrigerant container having a vertical flat wall substantially in contact with said upstanding flange and said upper vertical portion, means to secure said upstanding flange and said wall together, and a cradle positioned between said lower vertical portion and said wall and secured to said frame member.
